WIRELESS RECEIVING SYSTEM

Application filed April 12, 1928. Serial No. 269,337.

This invention relates to a system for receiving and converting wireless sound waves so as to properly actuate a receiver or loud speaker.

5 My improvement in such a receiving system resides in means pertaining to or utilizing and controlling regeneration in the vacuum tube used as a detector, said detector being preceded by at least one stage of radio frequency amplification, and also in means for controlling the volume of the sound waves delivered to the receiving instrument per se. A still further object of my invention is to provide ready means for converting the receiving set from one having regenerative action to one without such action, but having single control over the volume. Another object of my invention is to provide means for reducing the proportion of the radio frequency component of the detector plate current so as to modify the regenerative action. In order to illustrate my invention, I have chosen to illustrate it in connection with a series of vacuum tubes having filament, grid 15 and plate elements interlinked by suitable transformers, in which preferably the input circuits of the tubes preceding the detector tube are tuned, and

Figure 1 of the drawings accompanying 30 this specification, illustrates one form of receiving system in which I have chosen to show my invention. Figure 2 shows a modified form of the invention. In the drawings, 1, 2, 3, and 4, are radio frequency transformers, and 5 and 6 are audio frequency transformers. Transformer 1 has one end of its primary 11 connected to earth E, and has taps T to which the antenna A may be selectively connected to different number of turns in the primary 11 for well-known reasons.

40 Associated with the secondary 12, is a variable condenser 13 for tuning the circuit which is connected to the grid G of the first tube 10, which tube has the usual filament F and plate P. The primary 21 of the transformer 2 is connected to the plate P of tube 10, while the secondary 22 with its tuning condenser 23, is connected to a controlling resistance 24 to the 45 grid of tube 20. The resistances 24 and 34

are used for the purpose of suppressing the tendencies of tubes 20 and 30 to oscillate.

In similar manner, the primary 31 and secondary 32 of transformer 3 with tuning condenser 33, are used to interlink tube 20 to tube 30, the resistance 34 similar to 24 being used in the grid circuit of the tube 30. Tube 40 is used as a detector. Grid leak resistance 44 with its associated condenser 45 of low capacity, whose functions are old and well known, is connected to the grid of this tube and to the secondary 42 and tuning condenser 43 of transformer 4. Associated with the primary 41 of the transformer 4, is a resistance or potentiometer 35, having its extremities X and Y connected across or parallel with the winding 41.

The movable contact Z of the potentiometer is connected to one terminal of the switch S, the other terminal of which is connected to 70 the extremity X of the potentiometer. Movable contact Z is also connected with a condenser 46, the opposite terminal of which is connected to the plate P of the detector tube 40.

75 Tube 50 is associated with an audio frequency transformer 5, whose primary 51 is connected to the source of current supply for the plate circuit of detector 40, while the secondary 52 is connected to the input side of 80 the tube 50. Preferably associated or connected across the secondary 52 of the transformer 5, is a high resistance 54, which is used for the purpose of suppressing the tendencies of the audio frequency amplifier 50 to 85 oscillate.

Connected to the tube 50, is primary 61 of transformer 6, the secondary 62 of which is connected to the input side of tube 60. Associated with the filament of the detector tube 90 40, is a fixed center tapped resistance 48, having the center tap grounded for the purpose of reducing the excessive hum from this tube, it being understood as indicated by the designations, on the terminal post that alternating current is used to supply this receiving system with energizing power.

Connected across the filament of tube 60, is a similar resistance 64 for the purpose of establishing the electrical center of said fila- 10

ment. To the central point of this resistance, is connected a biasing resistance 65, the opposite end of which is grounded, thereby producing a bias for the tube 60, due to the plate current of this tube flowing through the resistance 65. A bypass condenser 63 is preferably utilized as indicated.

The loud speaker LS is adapted to be connected to the plate circuit in the manner shown. 71 is a fixed center tapped resistance, and 72 a potentiometer, both being placed across the filament tubes 10, 20, 30, and 50, for the purpose of establishing the electrical center of these filaments. 73 is a biasing resistance for tubes 10, 20, 30, and 50, which bias is produced by the plate currents of these tubes flowing through the resistance 73. A bypass condenser 80 is used in connection with the resistance 73, while a bypass condenser 81 is placed across the plate supply for the tubes 10, 20, 30, and 50.

My invention resides primarily in the arrangement involving the potentiometer 35 and the condenser 46 with an auxiliary condenser 47 which may in some cases be used. The potentiometer 35 has a resistance of the order of ten thousand ohms, and as has been pointed out, is connected across the primary 41 of the radio frequency transformer 4, the secondary of which leads into the grid circuit of detector tube 40. I have found the condenser 46 to give excellent results when of the order of .002 microfarads capacity.

In operation, when the movable contact Z of potentiometer is connected to point Y, a portion of the radio frequency component of the detector plate circuit passes through condenser 46, and then in parallel through the winding 41 of the transformer 4 and the potentiometer resistance 35. Since the resistance 35 is very high in comparison with the reactance of winding 41, a large proportion of radio frequency component coming through the condenser 46, passes through the winding 41 of the transformer 4, and under this condition, gives the maximum regenerative effect.

As the movable contact Z of the potentiometer is moved toward the point X, the less will be the amount of regenerative current flowing through the winding 41, and hence the amount of feed-back or regenerative action is reduced, until the movable contact Z reaches the point X, when no feed-back or regenerative action takes place. It is to be understood that the primary purpose of regeneration is to enable the reception of signals too weak to be received without regeneration, and as the incoming signals become stronger, the need for feed-back or regeneration is correspondingly reduced and the regenerative action is very simply controlled by the potentiometer action as described.

I have found that the same potentiometer which controls the regenerative action, may

also be utilized for volume control to reduce excessive volume. This action is brought about by means of the single pole switch S, which when in the open position as shown, allows the potentiometer to be operated for regenerative control; but when the switch is closed, the feed-back current coming from the condenser 46 is shunted away from both the potentiometer and winding 41, thereby cutting off the regenerative action and allowing the potentiometer to be operated for simple volume control, as the potentiometer then becomes a variable resistance associated with the primary 41 of the transformer 4.

In some cases a condenser 47 may be utilized for the purpose of reducing the proportion of the radio frequency component of the detector plate current which will flow through the condenser 46 to the potentiometer as described. This additional control due to condenser 47, may be governed by the size of the condenser 47, and if desired, this control action may be brought into use by a switch 49. It is to be understood that condenser 47 is not necessary, but is often times helpful in obtaining smoother regenerative action.

In Figure 2 I have shown a modified arrangement for obtaining control of the regenerative action previously referred to as well as volume control. By this latter arrangement, the switch S is eliminated and the point z extending from the resistance 35 to the condenser 46 is fixed so that the resistance lying between the point z and the point y is preferably of the order of about 500 ohms. The point x is connected to a movable contact 36 which may be moved over the entire length of the resistance 35.

When the movable contact 36 is at the point z or between z and y, no regeneration occurs, as the feed-back currents passing through condenser 46, will then flow directly through the section z-36 of resistance 35 to radio frequency ground, the same as in Figure 1. The section 36-y is always in shunt to the primary 41 of the transformer 4 and by variation of the resistance value of the section 36-y, the control of the volume of the set is affected.

When the movable contact 36 is on the opposite side of the tap z from the end y, as indicated in Figure 2, the feedback currents flowing through condenser 46, divide between the two paths—one z-36 and the other z-y primary 41, so that variation of the value of the section z-36 causes a variation of the quantity of the feed-back currents passing through the primary 41 of the transformer 4, and in this way varies the regenerative action.

Assuming that the contact 36 is controlled by a suitable member such as a rotating knob, it will be seen that a smooth increase from no volume to full regeneration will be readily

obtained by turning the control knob, whereby the contact 36 is caused to travel along the length of the resistance 35. Hence, the active working length of said resistance is that part between the point *y* and the contact 36 wherever it may be located along the length of the resistance 35.

In Figure 1, the active length of the resistance 35 is from *y* to *x* when the switch *S* is open, and this corresponds to the condition when 36 is at the extremity of 35 opposite to the point *y*. The operation of the movable contact 36 modifies the regenerative feature and eliminates it entirely when moved as above explained, the same as the operation of switch *S* eliminates the regenerative feature entirely.

Of course it is obvious that contact *z* and contact 36 may both be variable if desired, and other changes are of course contemplated, as long as these changes do not depart from the spirit of my invention and the scope of the appended claims.

Having thus described my invention, what I claim is:

1. In a receiving system for wireless waves which includes; at least one stage of radio frequency amplification including its associated vacuum tube and at least one stage of audio frequency amplification including its associated vacuum tube and a detector tube operatively connected on its input side with the radio frequency amplification stage and on its output side with said audio stage; means for utilizing and controlling regeneration in the detector tube including a potentiometer having its extremities connected in parallel with some part of the radio frequency stage connected to the input of the detector tube and a condenser connected between the plate of the detector tube and the movable contact member of the potentiometer.

2. In a receiving system for wireless waves, a detector tube provided with a coupling device having an input circuit leading to the detector; means for utilizing and controlling regeneration in the detector tube including a potentiometer having its extremities connected in parallel with some part of the radio frequency stage connected to the input of the detector tube and a condenser connected between the plate of the detector tube and the movable contact member of the potentiometer, means for reducing the effect of the current flowing through said condenser to said potentiometer contact, and means for eliminating the regenerative feature when not desired and utilizing the potentiometer for volume control of the receiving system.

3. In a receiving system for wireless waves, a detector tube provided with a coupling device having an input circuit leading to the detector, means for utilizing and controlling regeneration in the detector tube including a

potentiometer having its extremities connected in parallel with at least some portion of the coupling device feeding into the detector grid circuit and a condenser connected between the plate of the detector tube and the movable contact member of the potentiometer, and means for eliminating the regenerative feature when not desired and utilizing the potentiometer for volume control of the receiving system.

4. In a receiving system for wireless waves, a detector tube provided with a coupling device having an input circuit leading to the detector, means for utilizing and controlling regeneration in the detector tube including a potentiometer having its extremities connected in parallel with at least some portion of the coupling device feeding into the detector grid circuit and a condenser connected between the plate of the detector tube and the movable contact member of the potentiometer, and means for eliminating the regenerative feature when not desired and utilizing the potentiometer for volume control of the receiving system, said means consisting of a switch for establishing a short circuit from the low potential side of the potentiometer to the movable contact thereof.

5. In a receiving system for wireless waves a detector tube provided with a coupling device having an input circuit leading to the detector; means for utilizing and controlling regeneration in the detector tube including a potentiometer having its extremities connected in parallel with some part of the coupling device connected to the input of the detector tube and a condenser connected between the plate of the detector tube and the movable contact member of the potentiometer, said means also including a movable device capable of effecting a shunt circuit around that part of the potentiometer between the point *x* and the movable contact.

6. In a receiving system for wireless waves, a detector tube provided with a coupling device having an input circuit leading to the detector; means for utilizing and controlling regeneration in the detector tube including a resistance having at least one end connected with some part of the radio frequency stage connected to the input of the detector tube, a condenser connected between the plate circuit of the detector tube and some point on the resistance and means for connecting at least said point on the resistance to another part of the coupling device as and for the purposes described.

7. In a receiving system for wireless waves, means for utilizing and controlling regeneration and volume therein including, a potentiometer for regulating both, and means for eliminating the regenerative feature over at least some portion of the potentiometer when not desired, and utilizing at least the re-

remainder of the potentiometer alone for volume control.

87. In a receiving system for wireless waves, a detector tube provided with a coupling device having an input circuit leading to the detector, means for utilizing and controlling regeneration in the detector tube including a resistance having its active working extremities connected in parallel with at least some portion of the coupling device feeding into the detector grid circuit, a feed-back means connected between the plate of the detector tube and some point on the resistance means for bringing in at will, the regenerative feature and means for modifying the regenerative feature by changing the active length of said resistance.

9. In a receiving system for wireless waves, a detector tube provided with a coupling device having an input circuit leading to the detector, means for utilizing and controlling regeneration in the detector tube including a resistance having its active working extremities connected in parallel with some part of the coupling device connected to the input of the detector tube, a condenser connected between the plate of the detector tube and some point on the resistance, said means also including a movable device capable of effecting a shunt circuit around at least that portion of said resistance from the point x to the point z .

In testimony whereof, I affix my signature.
